ALFRED ROSEWOOD, OF SAN FRANCISCO, CALIFORNIA

WASTE AND OVERFLOW FIXTURE FOR BATH TUBS

Application filed August 10, 1928. Serial No. 298,824.

The invention relates to improvements in waste and overflow fixture especially adapted to bathtubs in which the bathtub plug or stopper is forced from its seat by other means than the customary chain-pulling method.

The objects of the improvement are: First: To discourage that improper condition of installation of the waste fixture where the stopper is located in the T in line with the overflow pipe, and therefore permit a considerable distance of unclean surface to be directly churned and washed by the water which the bather imagines is free from any septic contact.

Second: To afford facilities to automatically spray this rather unclean and forgotten portion of the waste fixture, and

Third: To lift the stopper from its seat by the pressure of the water in the supply water pipe, by merely pressing a knob that opens a valve at the overflow fixture. It can be placed at any convenient place.

Several forms of the invention are illustrated in the accompanying drawings in which Figure 1 shows a vertical section of the entire outlet and overflow fixture connected to a bathtub.

Figure 2 is a plan view of the outlet fixture with the stopper removed;

Figure 3 shows a vertical section taken on line 3—3 of Figure 1;

Figure 4, a vertical section taken along line 4—4 of Figure 1;

Figure 5, a section of the outlet fixture showing a slightly modified form for keeping the stopper from reseating;

Figure 6, a view similar to Figure 1, showing a modified form of outlet fixture;

Figure 7, a plan view of the outlet fixture shown in Figure 6; and

Figure 8, a vertical section through another modified form of outlet fixture.

Fig. 1 shows the overflow pipe 4 broken away at one end and 5 is the waste outlet fix-

ture. At 6 is shown the outlet in cross-section of the tub, and at 7 the overflow fixture. The overflow fixture is provided with a lug 8 which retains a special valve 9 screwed in from the inside and provides for connection with the supply water pipe. The valve has a metallic washer 10 seated on a gasket 12 and is opened by pressing on the knob 14 the stem of which is reduced in cross-section at 13 and carries spring 13' reacting on the valve body and the larger section of the stem. The valve body is provided with a groove or recess 15 and holes 15' that communicate with its central bore 15'' radially or otherwise.

Facing the lug 8 and encircling the valve-body at its circular groove is an annular flattened ring 17 having a projecting nipple 18 to which a tubing 19 is soldered so as to communicate with the said groove. The relatively long cylindrical body of the valve serves as a means of holding the overflow fixture to the bathtub perforation by the nut 22 screwed on it against the overflow plate 21 which can be made in any fancy design. The tubing 19 connects with a lug 20 which also holds a cylinder 26 enclosing two pistons 26' and 26 separated by a partition 28 to insure lifting power should the water pressure be low. Said circular partition is removable with the piston and its diameter is slightly larger than the lower bore of the cylinder to provide a suitable seat 28' for reaction as the water finds its way through the central channel 29 and under the upper piston 26' as well as its lower 26''. The cylinder wall is provided with openings 30 to allow for the escape of water which otherwise would interfere with the motion of the piston when the valve is open to dislodge the stopper of the bathtub waste. They also serve to spray and cleanse this section of the fixture in proximity to the tub outlet.

Since it only takes a slight pressure on the

80
85
90
95

valve knob 14 to dislodge the submerged stopper 39 of the full bathtub, provision is made to prevent the piston from returning and the plug reseating under the pressure of the bath water. A hole 30' is drilled in the upper piston 26' and a suitable tumbler 31 acts therein against a spring 31' so when the piston rises the rounded end of the tumbler 31 catches on the edge of the cylinder 26 at 31 and holds it there. While the pressure of the water is not sufficient to force the tumbler back for reseating the stopper, replacing of the stopper by hand may easily overcome the resistance of the spring.

15 The cylinder 26 performs an additional function by holding the upper and the lower members of the waste fixture fittings to the bathtub supplemented by two screws 25 entering lugs 23 in the lower fitting of the fixture.

20 See Fig. 3. The cylinder 26 is provided with a screw-driver slot 27 on the flange which rests on an annular rib 44 which is integral with the upper fitting with its concentric seat for the stopper. The lower piston disk 46 is pressed on the piston rod and is provided with a recess for packing materials 46'. The small quantity of water used by the cylinder is returned to the valve and finds its way out through a slot or hole 45 in the valve and is automatically closed when the valve is 30 opened. See Fig. 1.

A U shaped flat spring 32 may be secured to the plug 39 to prevent it from reseating as shown in Fig. 5. The plug may be conveniently fastened to the cylinder by means of U 35 spring 32 which is set to yield to a greater pressure than the water has on the plug and will readily catch on the rim of the cylinder and prevent its return. When this construction is used, the tumbler 31 of Fig. 1 is omitted. It is readily understood that instead of a movable piston actuating the stopper, a movable cap or sleeve 50 (see Figure 8) fitted on a cylindrical body 51 having perforation 40 that connects with a valve will also be satisfactory.

It is also evident that the plug can be lifted from its concentric seat by a water jet of sufficient volume and velocity reacting on a 50 lever of correct design. Figures 6 and 7 show such construction.

In this form, the pipe 19 terminates in a nozzle 35 on which rests the lever 36, hinged between two lugs 37 in the lower fitting which 55 lever communicates its motion to the stem 38 and the stopper 39.

To prevent the stem 38 from returning a rounded groove 40 is provided on it to engage a tumbler 41 housed in one of the stays 60 41 which supports the hub 43 in which the stem 38 is guided. This stay is formed integral with the upper fitting of the waste fixture.

A spring 42 forces the tumbler into the 65 groove when the stem is raised and holds the

stem in that position to prevent reseating of the stopper.

Although I have shown this invention to be applied to bathtub waste and overflow fixture, it is self evident that it can be applied to lavatory fixtures as well. 70

I am aware that prior to my invention the stopper in a bathtub and lavatories has been lifted from its seat by mechanical means contrived and operated by hand power in the overflow and waste fittings. I, therefore, do not claim such mechanical movements, but I 75 claim:

1. In a fixture of the character described having a discharge port, a stopper for closing the same and an overflow port, pressure-operated means for removing the stopper from its seat and a manual control mounted in the overflow port for the pressure means. 80

2. In a fixture of the character described having a discharge port, a stopper for closing the same and an overflow port, pressure operated means for removing the stopper from its seat and a valve for the pressure means mounted in the overflow port having 90 an operating stem projecting from the overflow port. 85

3. In a bathtub having a discharge port, a stopper for the same, an overflow port and a sewer pipe connecting with both ports, pressure-operated means for removing the stopper from its seat, and a control means for the 95 same comprising a conduit mounted in the sewer pipe in alignment with the overflow port, a valve housing threaded thereinto having a central bore, radial ports connecting therewith, an annular groove connecting with the radial ports, a ring surrounding the groove having a nipple communicating with the groove, a conduit leading from the nipple to the stopper actuating means and a valve for the housing having an operating stem extending through the overflow port. 100

4. In a fixture of the character described having a discharge port and a stopper for closing the same, pressure-operated means for removing the stopper from its seat, the said means comprising a cylinder mounted underneath the stopper, means for admitting a pressure medium thereinto from below, a piston movable in said cylinder having a plunger associated therewith for ejecting the stopper when the piston is raised and a port in the cylinder adapted to be uncovered by the rising piston for allowing the pressure medium to escape therethrough for spraying and cleansing the region below the stopper. 105

5. In a fixture of the character described having a discharge port and a stopper for closing the same, pressure-operated means for removing the stopper from its seat, the said means comprising a cylinder mounted underneath the stopper, means for admitting a pressure medium thereinto from below, a piston movable in said cylinder having a plunger 110

associated therewith for ejecting the stopper when the piston is raised and a port in the cylinder adapted to be uncovered by the rising piston for allowing the pressure medium to escape therethrough for spraying and cleansing the region below the stopper, the plunger having means associated therewith for yieldingly holding the plunger in stopper ejecting position.

10 In testimony whereof, I have hereunto set my hand at San Francisco, California, this sixth day of August, 1928.

ALFRED ROSEWOOD.
